[57] CLAIM

The ornamental design for a dental stain removal tool, as shown and described.

DESCRIPTION

FIG. 1 is a perspective view of the dental stain removal tool embodying my inventive design;

FIG. 2 is a side view of the dental stain removal tool of FIG. 1;

FIG. 3 is a top view of the dental stain removal tool of FIG. 1;

FIG. 4 is a bottom view of the dental stain removal tool of FIG. 1;

FIG. 5 is an end view taken from the left end thereof, of the dental stain removal tool of FIG. 1; and

FIG. 6 is an end view taken from the right end thereof, of the dental stain removal tool of FIG. 1.
